PENCIL

Edward Turnberger, Newark, N. J.

Application August 3, 1931, Serial No. 554,865

8 Claims. (Cl. 120—14)

My invention relates to pencils and more particularly to mechanical pencils consisting of a holder provided with a compartment within which there is a container for holding a supply of leads and for holding an eraser, together with mechanical means for holding and feeding a lead at the writing end of a pencil. There are several distinct features in my invention, all of which combine to produce a very simple, effective and economical device.

One object of the invention is to provide an inner tubular member adapted to be held within the shell or barrel of the pencil and to be removed therefrom and this member or magazine is adapted to hold a supply of leads and to hold an eraser attached to one end thereof. This member has one or more apertures in the end opposite to that in which the eraser is held and the end having the aperture or apertures is adapted to be inserted into one of the barrel members so that the eraser may be used without removing the magazine from the barrel member. The leads may be individually removed from the magazine through the aperture or apertures in the end opposite to the eraser and so that it is not necessary to remove the eraser from the magazine for the purpose of removing the lead.

Another object of the invention is to provide, in conjunction with the tubular lead magazine, an eraser as above described, against which the leads at one end may rest and to provide a rubber or soft cushion within one of the barrel members and against which the opposite ends of any of the leads which project through the aperture or apertures in the magazine will strike or rest. Thus, the opposite ends of the leads will not strike or rub against hard or rigid materials and there is less likelihood of their being broken.

Another object of my invention is to provide means for facilitating the removal of the individual leads from the lead magazine. This is in the form of a sliding member, preferably in the nature of a metallic sleeve which may slide back and forth longitudinally within the lead magazine and by disturbing the leads, tend to lead them toward one end of the lead holding member and prevent them from adhering to the inner surface of the magazine. This sliding sleeve is also adapted to align the leads with the discharge aperture or apertures, the latter being disposed off the axis of the magazine so that the leads are guided by the sliding sleeve in line with the discharge aperture or apertures. By simply shaking or tilting the magazine, a single lead will feed readily through one of the discharge apertures.

If there are two discharge apertures arranged opposite each other, each time the tube is shaken or tilted at least one lead will be projected through one of the apertures and very often a lead will be projected through each of the apertures, in which latter case one will be grasped and removed and the other being allowed to fall back into the magazine. Other advantages of the invention will be set forth in the following detailed description.

In the drawing forming part of this application,

Figure 1 is an elevational view of a pencil embodying my invention.

Figure 2 is a longitudinal, sectional view taken on the line 2—2 of Figure 1.

Figure 3 is an assembly view showing the several parts of the device in the order of their assembly.

Figure 4 is a cross sectional view taken on the line 4—4 of Figure 2, and

Figure 5 is a cross sectional view taken on the line 5—5 of Figure 2.

As far as my present invention is concerned any mechanical device for projecting and retracting the lead at the writing end of the pencil may be used, and I have omitted showing details of this portion of the device. I have shown a barrel consisting of the section 1 to which the conical portion 2 of the lead operating device is attached, together with a tubular member 3 which forms the upper or second section of the barrel. This latter member usually has a solid or closed end 4 and it also has a longitudinal bore 5 into which tightly fits the metal sleeve 6 the latter projecting at 7 at the open end of the barrel member so that it fits slidably into the metal lining 8 which is fitted into the bore 9 of the first barrel section 1. This metal sleeve 6 forms both a lining for the bore of the member 3 and also as a means for detachably holding the barrel members together. The ring 10 shown surrounding the open end of the barrel member 3 is partly for ornamental purposes and partly to prevent the barrel member from splitting near its open end. Within the metal lining 6 of the barrel member 3 I have applied an abutment member 11 of soft material, preferably rubber, which is pressed into the lining member and remains permanently in its inner end, as shown in Figure 2.

The lead holding magazine is shown as a cylindrical member 12 having a longitudinal bore 13 and adapted to slide freely into and out of the lining member 6. One end of this tube 12

is open and the eraser 14 is adapted to fit snugly into this open end and to project partly beyond it so that it may be used for erasing purposes. The opposite end of this tube has an end wall 15 provided with one or more apertures 16 of sufficient size to permit an individual lead to pass therethrough; and I prefer to provide two such apertures arranged on opposite sides of the axial line of the tube, although the number of apertures may be greater or less. These apertures communicate with the bore 13 of the magazine 12. The several leads 17 are adapted to be retained within the tubular member 12 between the eraser 14 and the end wall 15. To prevent the leads from adhering to the interior surface of the magazine and entangling with each other and failing to feed down to the discharge apertures 16, I have provided a member for urging the leads toward the latter apertures; and this is shown in the form of a cylindrical sleeve 18, preferably made of metal and of sufficient weight to slide freely back and forth within the bore 13 of the tube 12 when the latter is tilted. The leads extend through the bore of this cylindrical agitator as shown in Figure 2. The thickness of the wall of the agitator is such as to cause its inner surface to register with the outer portions of the apertures 16 so that when the agitator is resting against the end wall 15 of the tube 12 there will be a tendency for at least one lead to be presented in line with each discharge aperture 16, but if leads are not presented to both apertures, at least one lead can generally be presented in line with one of the apertures. It will be noted that the lead magazine is applied to the barrel member 3 so that the end wall 15 having the lead discharge apertures 16 is enclosed within the barrel member, whereas the end having the eraser projects from this barrel member. When the device is used for writing as shown in Figure 1, the two barrel members are fitted together with the lining member 6 of one barrel member frictionally engaging within the bore of the lining member 8. In this condition the pencil may be used for writing with one of the leads supplied to the mechanical feed device, as shown at 19. It may be noted that this type of pencil belongs to the class wherein individual leads are supplied to the mechanical feeding device by withdrawing a lead from the magazine tube 12 and placing it into the mechanical feed device from the outside. If it is desired to use the eraser the barrel member 3 is simply detached from the barrel member 1 and the lead magazine tube will remain with the barrel member 3 and it may be manipulated for the purpose of rubbing the projecting end of the eraser over the pencil marks which are to be erased. After the eraser has been used the barrel members may be attached together as shown in Figure 1. If it is desired to place a new lead in the mechanical feed device, the barrel members are separated and the lead magazine tube 12 is withdrawn from the lining member 6, or in other words, it is detached from the remainder of the pencil. The lead magazine is then tilted so that the end wall 15 is pointed down and this causes the slider 18 to move down toward the end wall 15 and to urge the leads in the same direction.

Usually, at least one lead will line up with one of the discharge apertures 16 and will project partly through it so that the lead may be grasped in the fingers and entirely removed from the magazine. This lead may be presented from the

outside to the mechanical feed device in the usual way. It will be noted that in removing the lead from the magazine it is unnecessary to detach the eraser 14 from the end of the magazine.

When the magazine is in place within the barrel, the leads at one end may rest against the eraser 14 which is soft and will not injure the leads. If a lead should extend through one or both of the apertures 16 it will rest against the soft cushion 11 and this end of the lead will not be damaged.

Having described my invention, what I claim is:

1. A barrel composed of separable hollow sections, one of said sections having a closed end, a lead magazine, a removable plug for closing one end of said magazine and projecting beyond the end thereof, said magazine having its opposite end provided with an aperture to permit the individual leads to be withdrawn therethrough, said lead magazine being insertable into said second mentioned barrel section so that the plug projects from said second barrel section and with its apertured end disposed toward the apertured end of said second mentioned barrel section.

2. A barrel composed of separable hollow sections, one of said sections having a closed end, a lead magazine, a removable plug for closing one end of said magazine and having its opposite end provided with an aperture to permit the individual leads to be withdrawn therethrough, said magazine being insertable into the said second mentioned barrel section with the apertured end directed toward the closed end of said second mentioned barrel section.

3. A barrel composed of separable hollow sections, one of said sections having a closed end, a soft abutment member adjacent said closed end of said second mentioned section, a lead magazine, a removable plug for closing one end thereof, said magazine having its opposite end provided with an aperture to permit the individual leads to be withdrawn therethrough, said lead magazine being insertable into said second mentioned barrel section so that said abutment member will lie adjacent the apertured end of said magazine.

4. A barrel composed of separable hollow sections, one of said sections having a closed end, a lead magazine, a removable plug for closing one end of said magazine and projecting from one end thereof, said magazine having its opposite end provided with an aperture disposed eccentric to the bore of said magazine to permit individual leads to be withdrawn therethrough, said lead magazine being insertable into said second mentioned barrel section whereby the lead discharging end of said magazine is directed toward the closed end of said second mentioned barrel section.

5. A magazine for holding a supply of leads and adapted to be inserted into the barrel of a pencil, said magazine having a discharge aperture for the individual leads and a member freely slidable in said magazine for agitating the leads.

6. A lead magazine for pencils including a tubular body adapted to hold a supply of leads and having an end provided with an aperture for the discharge of individual leads therethrough and a sleeve freely slidable in the bore of said magazine and adapted to agitate the leads therein.

7. A magazine for pencils, comprising a tubular member having an end wall provided with an aperture for the discharge of individual leads, and a sleeve freely slidable in said magazine, said discharge aperture being disposed eccentrically in relation to the axis of the magazine and the in-

terior surface of said sleeve substantially coinciding with the outer portion of said discharge aperture, whereby said sleeve will direct the leads towards said discharge aperture.

5 8. A barrel composed of separable hollow sections, one of said sections having a closed end, a lead magazine, a removable plug for closing one end of said magazine and projecting from one end thereof, said magazine having its opposite 10 end provided with an aperture to permit individual leads to be withdrawn therethrough, said

aperture being disposed eccentric to the axis of said magazine, said magazine being insertable into said second mentioned barrel section so that the eraser projects from said latter section and its apertured end is directed towards the closed end of said second mentioned barrel section, and a cylindrical sleeve disposed in said magazine and adapted to slide freely therein and co-operating to agitate the leads in said magazine and to direct them towards said discharge aperture.

EDWARD TURNBERGER.
